GARMENT CONSTRUCTION

Barney Latter, Chicago, Ill., assignor to J. B. Simpson, Inc., Chicago, Ill., a corporation of Illinois

Application June 8, 1944, Serial No. 539,276

6 Claims.

(Cl. 2—234)

The invention pertains to a novel construction for women's slacks and the like, and its general object is to provide an improved placket in association with one of the side pockets with a view to improving the appearance and reducing the cost of manufacture.

More specifically stated, the invention has for a further and important object the provision of a placket in association with a side pocket in a pair of slacks or the like in such a way as to conceal effectually the detachable connection normally closing the placket and this notwithstanding gapping of the pocket opening.

The objects of the invention thus generally stated together with other and ancillary advantages are attained by the construction and arrangement shown by way of illustration in the accompanying drawing, in which:

Fig. 1 is a perspective view of a pair of slacks embodying the invention.

Fig. 2 is a perspective three-quarter view looking from the rear of the garment shown in Fig. 2 at the wearer's left-hand side and showing the placket in partially open condition.

For purposes of illustration, I have shown my invention as embodied in a pair of women's slacks having front and rear sections 10 and 10' joined by vertical side seams 11, one only being shown. The usual side pockets 12 and 12' are also provided, and in accordance with the present invention, a placket 13 is associated with the outer wall of one of the side pockets (herein the left-hand pocket 12) in such a way as to conceal effectually a slide fastener connection 14 normally closing the placket.

The pocket 12 is suitably attached to and suspended from the rear portion 15a of the usual waistband 15, and the normally closed placket opening extends vertically along the outer wall 12a of the pocket near the rear edge of the pocket opening. The inner wall 12b of the pocket is preferably extended rearwardly substantially beyond the rear edge of the outer wall 12a and is suitably attached to the rear section 10' of the garment at the inner side of such section, preferably along the side seam 11.

A facing strip 18 is projected from the vertical seam 11 forwardly into the pocket opening, for the sake of appearance, and preferably the inner edge of this strip is stitched to the inner wall 12b of the pocket. Also, the upper rear edge portion of the front section 10, which is left free on account of the pocket opening, is provided on its inner side with a welt 19 to form an inner facing

for the inner rear edge portion of the outer pocket wall, the construction being conventional except that one edge portion of the welt is also free for a purpose which will presently appear.

5 The slide fastener 14 provides a disengageable connection between the welt 19 and the rear edge of the outer pocket wall 12a. The slide fastener is of conventional construction, comprising two fastener strips or webs 14a and 14b, one secured to the rear edge of the outer pocket wall 12a and the other secured to the free edge of the welt 19 on the front section 10 of the garment. When these two strips are interlocked to close the placket, the welt forms in effect a continuation or rearward extension of the outer pocket wall, the edge of the welt being free. The upper extreme portion of the placket opening is held closed by suitable fasteners such as a pair of buttons 20 and 21 respectively secured on the inner side of the front 10 overlapping portion 15b of the waistband and on the front side of the rear underlapping portion 15a of the waistband, it being understood that the cooperating parts of the band are formed with suitable buttonholes 22 and 23.

15 20 25 In practice, the pockets are of course prepared separately and stocked for subsequent use. As thus prepared, they may be equipped with a fastener strip 14b constituting one-half of a slide fastener. This permits of a substantial saving in time in the actual making of the garment.

It will be observed that the pocket, being suspended from the rear portion of the waistband and secured to the inner face of the rear section 10' of the garment, serves as a covering strip for the inner edge portions of the cloth where joined by the vertical seam 11. In prior constructions, a separate covering strip is commonly employed for this purpose.

20 25 30 35 40 45 50 55 Of primary importance is the disposition of the placket opening so as to be concealed effectually from view notwithstanding gapping of the pocket opening. This is made possible by suspending the pocket from the rear portion of the waistband and by locating the placket opening between the rear edge of the outer pocket wall and the welt 19 forming an inner facing for the front pocket wall 12a. Heretofore, the common practice has been to suspend the pocket from the front overlapping end portion of the waistband and to form the placket opening between the rear edge of the inner pocket wall and the rear portion 10' of the garment. This has necessitated the use of a covering strip overlying the slide fastener closing the placket, which covering strip not only adds to the cost and bulk of the garment but

does not effectually conceal the zipper fastening in the event of gapping of the pocket opening. In brief, by the construction and arrangement employed, a substantial improvement in appearance is effected and at the same time the cost of production is materially reduced.

I claim as my invention:

1. A garment construction of the class described comprising, in combination, front and rear sections joined in a vertical side seam with a waistband open at such side and having a front overlapping end portion adapted to be secured detachably to an underlying rear portion, a pocket suspended from said rear portion of the waistband and opening rearwardly, said pocket having an extended rear wall attached to the rear section of the garment at the inner side thereof and a front wall terminating short of the rear edge of the front section of the garment, a welt secured to the edge of said front section upon the inner side thereof and having a free edge, a slide fastener detachably connecting said welt and the rear edge of the pocket front wall to form a placket, said fastener having two attaching webs respectively secured to the free edge of said welt and to the rear edge of the outer pocket wall, and a facing strip attached to the rear wall of the pocket in opposed relation to said welt, said facing strip being joined to the rear section of the garment by said vertical seam.

2. A garment construction of the class described comprising, in combination, front and rear sections joined in a vertical seam with a waistband open at one side having a front overlapping end portion adapted to be detachably secured to an underlying rear portion, a pocket suspended from said rear portion of the waistband and opening rearwardly, said pocket being attached to the inner side of the rear portion of said waistband and having a rear wall attached to the rear section of the garment at said vertical seam, and a placket having a disengageable slide fastener connection between the rear edge of the front wall of the pocket and the front section of the garment.

3. A garment construction of the class described comprising, in combination, front and rear sections joined in a vertical side seam and having a waistband open at such side with a front portion overlapping the rear portion for a sub-

stantial distance, a pocket suspended from and attached to said rear portion of the waistband and to the rear section of the garment, the front section of the garment having a welt at its rear edge below the waistband, and a slide fastener detachably connecting said welt with the rear edge of the outer wall of the pocket.

4. A garment construction of the class described comprising, in combination, front and rear sections joined in a vertical side seam and having a waistband open at such side with a front portion overlapping the rear portion for a substantial distance, a pocket suspended from and attached to said rear portion of the waistband and to the rear section of the garment, the front section of the garment having an inner welt at its rear edge below the waistband, a slide fastener detachably connecting said welt with the rear edge of the outer wall of the pocket, and a facing strip extending forwardly from said vertical side seam into the pocket opening and secured to the inner wall of the pocket.

5. A garment construction of the class described comprising, in combination, a rear section and a front section, a waistband to which said two sections are attached, said waistband being open at one side and having overlapping front and rear portions with means for securing the front portion in overlapping relation to the rear portion, and a pocket suspended from the rear portion of the waistband and opening rearwardly with the rear edge of its outer wall detachably connected to the front section of the garment to form a normally closed placket.

35 6. A garment construction of the class described comprising, in combination, a rear section and a front section, a waistband to which said two sections are attached, said waistband being open at one side and having overlapping front and rear portions with means for securing the front portion in overlapping relation to the rear portion, and a pocket suspended from the rear portion of the waistband and opening rearwardly with the rear edge of its outer wall detachably connected to the front section of the garment to form a normally closed placket, the inner wall of said pocket being secured to said rear section.

BARNEY LATTER.
